PISTON FOR INTERNAL COMBUSTION MOTORS

Elmer C. Long, Grosse Pointe Park, Mich.

Application October 14, 1935, Serial No. 44,815

9 Claims. (Cl. 309—13)

This invention relates to pistons for internal combustion motors, and pertains more particularly to pistons made of an aluminum alloy metal, and having the cylinder bearing walls or sections 5 of the skirt disconnected from the side wall of the head and resiliently and flexibly connected to the pin bosses.

The invention is a furthering of the improvements in pistons disclosed in U. S. Letters Patent 2,017,630 and 2,068,341, granted to me October 15, 1935, and January 19, 1937, respectively, the instant application having distinctly different and specific features, not disclosed in either of said patents.

15 The main object of the invention is to provide a piston whereby thermal expansion of the head on a diameter across the pin bosses, is made co-actable with the skirt sections through webs or supports from the pin bosses to the sections, so 20 that the piston structure will act to prevent the skirt sections seizing with the cylinder wall, as the piston grows or expands under heat.

Another object of the invention is to provide a piston having a pair of opposing slipper sections 25 with a specific form of supporting webs for one skirt section and another form of supporting webs for the other skirt section, and with means co-operable with the webs of one of the skirt sections for providing adjustment thereto.

30 Other objects and advantages will appear as this description progresses and by reference to the drawing, in which:

Figure 1 is a view in side elevation of a piston constructed in accordance with my invention.

35 Figure 2 is a vertical sectional view taken approximately on the line II—II of Fig. 1.

Figure 3 is a vertical sectional view taken approximately on the line III—III of Fig. 2.

Figure 4 is an open end view of the piston 40 shown in Fig. 1.

Figure 5 is a horizontal sectional view taken approximately on the line V—V of Fig. 2.

Figure 6 is a horizontal sectional view taken approximately on the line VI—VI of Fig. 2.

45 Referring to the drawing, this improved piston comprises a head 1 having a side wall 2 with packing ring recesses 3 on its outer periphery, and depended from the side wall 2 in opposite disposition, are a pair of legs 4 and formed integral with the lower end of each leg, is a pin boss 5. Each leg 4 where it joins with the side wall 2 of the head has an inwardly and downwardly inclining portion 6, for disposing the legs 4 inwardly so that they join with respective pin bosses at

the inner ends thereof, as shown in Figs. 2, 5 and 6.

Integrally joined with the head 1 and the side wall 2 thereof is a web 7, said web paralleling the pin bosses and being disposed on one side of the axial center of the pin boss axis, toward the power thrust side A of the piston skirt and having downwardly extending end portions 8 which are joined with the inner surfaces of respective pin boss legs 4.

10 The end portions 8 of the web 7 are relatively wide in thickness and by reason of said web 7 being disposed offset to the axial center of the pin boss axis, the end portions 8 are also disposed offset to the pin bosses 5 (Figs. 4, 5 and 6), 15 where they join with the inner ends of respective pin bosses, at the top and bottom thereof, as shown in Figs. 1, 2 and 3.

20 The power thrust side A of the piston skirt comprises a cylinder bearing slipper section 9 which is indirectly connected to the pin bosses 5 by a pair of webs 10 which diverge from the intermediate portion of the slipper section 9 and are joined at their opposite ends with respective end portions 8 of the web 7.

25 Oppositely disposed from the power thrust side A is the compression thrust side B of the piston skirt, which comprises a pair of cylinder bearing slipper sections 11 which are separated from one another by a longitudinal slot 12 which 30 extends from end to end of said slipper sections, each slipper section 11 being indirectly connected to a respective pin boss by a web 13, each web 13 joining with a respective end portion 8 of the web 7 at its inner end.

35 Connecting the webs 13 at points intermediate their length, is a tie bolt 14 having pairs of lock nuts 15 thereon, said tie bolt if desired, being of a material having a lesser co-efficient of expansion than the material of the piston proper, said tie 40 bolt being capable of manipulation for providing adjustment to the slipper sections 11 for drawing them towards each other or for adjustably separating them.

45 The arrangement of the end portions 8 of the web 7 is such wherein they provide connectors for the inner ends of the webs 10 and 13, to the inner ends of respective pin bosses 5, above and below the pin bores of the pin bosses, as designated at 16 and 17 respectively. The webs 10 and 13 at their juncture with respective end portions or connectors 8 of the web 7, are formed with an auxiliary pin boss 18, each of which is provided with a pin bore in alignment with the pin 50 55

bores of the pin bosses 5, and through which a piston pin (not shown) is mounted.

The pin bores of the auxiliary pin bosses 18 may be horizontally elongated if desired, to permit ease of flexing of the webs 10 and 13 when the inner ends thereof, fulcrum at the end portions or connectors 8 of the web 7, when the pin bosses 5 are moved outward by expansion of the head 1 of the piston, or when the pin bosses are moved inward due to contraction of the piston head.

The slipper sections 9 and 11 which provide the skirt for the piston are separated from the side wall 2 of the head by transverse slots 19, and when a piston of this improved character has been completely finished ready for mounting in the cylinder of an internal combustion motor, if desired, a nicety of fit can be provided by manipulating and securing the tie bolt 14 in a manner to provide a required setting of the slipper sections 11 on the compression thrust side B of the piston skirt, so that a minimum of working clearance may be acquired on a diameter across the thrust sides A and B, in respect to the cylinder in which the piston is to be reciprocably mounted.

At the present time, pistons of this character are preferably made of an aluminum alloy metal and which metal while having resiliently yieldable characteristics, has a larger co-efficient of expansion than the cast iron cylinder in which the piston is mounted. In the operation of this improved piston, expansion of the head 1 of the piston on a diameter across the legs 4 of the pin bosses 5, will carry the pin bosses outwardly from one another to a maximum extent because of the material thickness of the web 7 which parallels the pin bosses, and consequently, the joined ends of the webs 10 and 13 by reason of being connected to the inner ends of the pin bosses by the end portions 8 of the web 7, the inner ends of the webs 10 and 13 and the auxiliary pin bosses 18, will also be carried outwardly and the webs 10 and 13 will be affected thereby in the following manner:

The webs 10 when having their inner ends moved outwardly from one another by expansion of the head, will tend to exert a pulling force on the outer ends of said webs where they connect with the slipper section 9, with a consequent pulling or holding in of said slipper section, and as said webs converge from their points of connection with the auxiliary pin bosses 18 and/or the connectors 8 on one side of the pin boss axis and on the power thrust side of the skirt, the drawing-in action of the slipper section 9 by the spreading of the inner ends of said webs, will operate faster than if said webs were connected at the pin boss axis. The action of the outwardly moving pin bosses on the webs 13, due to expansion of the head, will spread the inner ends of said webs, and the tie bolt 14 on account of its intermediate connection therewith, will cause the intermediate portions of the webs to fulcrum at the points where they are engaged by the tie bolt 14 and the outer ends of said webs where they join with respective slipper sections 11, will be swung inwardly in a manner wherein said slipper sections 11 will tend to be moved towards each other, thereby in a manner holding the peripheries thereof from seizing engagement with the cylinder wall due to expansion of the piston as a whole.

The offset disposition of the web 7 and its end portions 8 with respect to the pin boss axis,

on the power thrust side of the piston, provides for a counterbalancing of the tie bolt 14 and its locking nuts 15, on the compression thrust side of the piston. The connectors 8 or end portions of the web 7, also provide for a common fulcrum 5 for each set of webs 10 and 13, for enhancing the flexing activity of the inner ends of said webs 10 and 13.

As shown in Figs. 4, 5 and 6, each slipper section 11 circumferentially tapers in wall thickness 10 from a maximum at their points of support with respective webs 13, to a minimum at their free ends at the longitudinal slot 12, for providing resilient yieldability to said sections and the compression thrust side B of the piston.

Having thus described my invention so that those skilled in the art will be able to practice the same, what I desire to secure by Letters Patent is defined in what is claimed, it being understood that various changes in the piston shown 20 and described above in detail and not amounting to invention may be made without departing from the spirit and scope of my invention.

What I claim is:

1. A piston having a head and pin bosses depending therefrom, and a single web extending across the head and paralleling the pin bosses, said web being disposed on one side of the axial center of the pin bosses and being the only web extending across the head of the piston.

2. A piston comprising a head having a side wall, a pair of opposing pin boss supports depending from the side wall, and a single web extending across the head parallel to the pin boss supports and having end portions joining the pin 35 boss supports, said web being disposed on one side of the axial center of the piston and being the only web extending across the head.

3. A piston comprising a head, a skirt having a compression thrust side and a power thrust 40 side, pin bosses, a single web extending across the head and paralleling the pin bosses on one side of the axial center of the pin bosses on the power thrust side of the skirt, said web being the only web extending across the head and having 45 end portions joining the inner ends of respective pin bosses, and a wall extending at right angles from each end portion of said web to the compression thrust side of the skirt.

4. A piston comprising a head, a skirt having a compression thrust side divided into a pair of slipper sections, and a power thrust side, pin bosses, and a single web extending across the head and paralleling the pin bosses on one side of the axial center of the pin bosses on the power thrust side of the skirt, said web being the 55 only web extending across the head.

5. A piston comprising a head, a skirt having a compression thrust side, and a power thrust side, pin bosses, a single web extending across 60 the head and paralleling the pin bosses on one side of the axial center of the pin bosses on the power thrust side of the skirt, said web being the only web extending across the head and having end portions joining the inner ends of respective pin bosses, and angular walls extending from each end portion of said web to respective thrust sides of the skirt.

6. A piston comprising a head, a skirt having a compression thrust side divided into a pair of 70 slipper sections and a power thrust side, pin bosses, a web extending across the head and paralleling the pin bosses on one side of the axial center of the pin bosses on the power thrust side of the skirt, said web being the only web extend-

ing across the head and having end portions joining the inner ends of respective pin bosses, and a wall extending at right angles from each end portion of said web to a respective slipper section of said compression thrust side.

5 7. A piston comprising a head, a skirt having a compression thrust side divided into a pair of slipper sections and a power thrust side, pin bosses, a single web extending across the head 0 and paralleling the pin bosses on one side of the axial center of the pin bosses on the power thrust side of the skirt, said web having end portions joining the inner ends of respective pin bosses and being the only web extending across the 5 head, a wall extending at right angles from each end portion of said web to a respective slipper section of said compression thrust side, and a tying member connecting the intermediate portions of said walls.

0 8. A piston comprising a head, a skirt having a compression thrust side divided into a pair of slipper sections and a power thrust side, pin bosses depended from the head, a web extending across the head on one side of the axial center

of the piston and paralleling the pin bosses and having downwardly extending end portions each joining the inner end of a respective pin boss, said web being the only web extending across the head, a wall extending at right angles from each end portion of said web to a respective slipper section of said compression thrust side, and a pair of diverging walls extending from the medial portion of said power side, each being connected at their inner ends to a respective end 10 portion of said web.

9. A piston comprising a head, a skirt having opposing thrust sides, a pair of legs depending from the head, a pin boss carried by each leg, a web extending across the head parallel to the pin bosses and having downwardly extending end portions joining with the legs and the inner ends of the pin bosses above and below the pin boss bores, said web and the end portions thereof being disposed offset with respect to the axial center of the piston, and a wall extending from each side of respective end portions of said web to respective skirt thrust sides.
